Specification for Design.

Patented June 15, 1915.

Application filed January 4, 1915. Serial No. 524. Term of patent 3½ years.

To all whom it may concern:

Be it known that I, EDGAR MOTT BOTTOOME, a citizen of the United States, and residing at Moundsville, in the county of Marshall and State of West Virginia, have invented a certain new, original, and ornamental Design Applied to a Glass Vessel or Similar Article, of which the following is a specification, reference being had to the accompanying drawings, forming a part thereof, wherein—

Figures 1 and 2 are elevations of a glass vessel illustrating different portions of the superficial ornamentation applied thereto.

Copies of this patent may be obtained for five cents each, by addressing the "Commissioner of Patents, Washington, D. C."

The design is shown applied to a tumbler of conventional form, the shape of which is not claimed.

I claim:—

The ornamental design applied to a glass vessel or similar article, substantially as shown.

EDGAR MOTT BOTTOOME.
